UNITED STATES PATENT OFFICE.

SAMUEL H. TURNER, OF BUCKHANNON, WEST VIRGINIA.

DESIGN FOR A BED-SPRING.

SPECIFICATION forming part of Design No. 17,951, dated December 13, 1887.

Application filed October 7, 1887. Serial No. 251,768. Term of patent 14 years.

To all whom it may concern:

Be it known that I, SAMUEL H. TURNER, a citizen of the United States, residing at Buckhannon, in the county of Upshur and State of 5 West Virginia, have invented a new and useful Improvement in Design for Bed-Springs, of which the following is a specification.

My invention relates to a new and original design for bed-springs of the class known as 10 "twin springs," which is hereinafter more fully described, and specifically pointed out in the claim.

In the drawing I have shown a plan view of my design.

15 Referring by letter to the drawing, A designates the two coiled sections of the spring, the upper coils, B B, of which sections are bent into the form of horseshoes. The toe portion of the said horseshoes is tapered or 20 pointed, as seen at G, and the heel or frog thereof is formed by a re-entrant obtuse angle, (clearly shown at C C.)

D designates the continuous wire of the sections, and it is bent to form oppositely-extending loops E E of approximately horseshoe 25 shape, and the sides of the loops are provided (by bending) with obtuse angles F F, which correspond in shape and size with the angles in the heels of the horseshoes B B. The sides 30 of the angles F F are so arranged as to be parallel with the sides of the angles C C, as will be seen by the drawing.

Each side of each loop E is provided with

two angles—an external and a re-entering angle; but, as the loops extend in opposite directions, the external angle of one loop corresponds with the re-entering angle of the other loop. The corresponding angles on opposite sides of the same loop, however, are similar—that is, they are either external or re-entering. 40

The present design corresponds in general characteristics with the design covered by the patent granted to me on March 27, 1883, and bearing the number 13,820; but the specific arrangement of the present design is different 45 from that shown in the said patent, as will be seen upon comparison.

I claim—

The design for twin bed-springs, consisting of the upper coils of the springs bent into 50 horseshoe form, with the toes thereof tapered or pointed and the heels or frogs formed by obtuse re-entrant angles, and a continuous wire between the springs forming oppositely-extending horseshoe loops F F, having their 55 sides provided with exterior and re-entrant angles arranged alternately with their sides parallel with the frogs, substantially as specified.

In testimony that I claim the foregoing as 60 my own I have hereto affixed my signature in presence of two witnesses.

SAMUEL H. TURNER.
